(57) **CLAIM**

I claim the ornamental design for a top portion of a pair of jeans, as shown and described.

DESCRIPTION

FIG. 1 is a rear perspective view of a top portion of a pair of jeans showing my new design;

FIG. 2 is a front elevational view of the invention;

FIG. 3 is a rear elevational view of the invention;

FIG. 4 is a right-side elevational view of the invention;

FIG. 5 is a left-side elevational view of the invention;

FIG. 6 is a top plan view of the invention; and,

FIG. 7 is a bottom plan view of the invention.

The broken lines in FIG. 1 showing a portion of the human figure illustrate the invention is use and form no part of the claimed design.

The broken lines, shown throughout the views, on the surface of the jeans represent stitching.
